US00D776329S

(12) **United States Design Patent** (10) **Patent No.:** **US D776,329 S**
Dyson et al. (45) **Date of Patent:** **** Jan. 10, 2017**

(54) **LIGHT FIXTURE**(71) Applicant: **Dyson Technology Limited**, Wiltshire (GB)(72) Inventors: **Jacob Dyson**, London (GB); **Douglas Andrew Inge**, London (GB); **Samuel Emrys James**, London (GB)(73) Assignee: **Dyson Technology Limited**, Malmesbury, Wiltshire (GB)(**) Term: **15 Years**(21) Appl. No.: **29/551,543**(22) Filed: **Jan. 14, 2016****Related U.S. Application Data**

(62) Division of application No. 29/502,359, filed on Sep. 15, 2014, now Pat. No. Des. 750,830.

(30) **Foreign Application Priority Data**

Mar. 14, 2014 (EP) 002425777-0001
 Mar. 14, 2014 (EP) 002425777-0002
 Mar. 14, 2014 (EP) 002425777-0003

(57) CLAIM

The ornamental design for a light fixture, as shown and described.

DESCRIPTION

FIG. 1 is a perspective view of the light fixture showing our new design;

FIG. 2 is a front view thereof;

FIG. 3 is a rear view thereof;

FIG. 4 is a top plan view thereof;

FIG. 5 is a bottom plan view thereof; and,

FIG. 6 is a side view thereof.

The broken lines shown illustrate portions of the light fixture that form no part of the claimed design.
